BRUSH DISPLAY

Lawrence R. Schumann, Boston, Mass.

Application January 22, 1957, Serial No. 44,548

Term of patent 14 years

(Cl. D80—5)

Fig. 1 is a view in front elevation of a brush display showing my new design, and

Fig. 2 is a view in side elevation of the brush display.

The broken line representation is for purpose of illustration only.

The drawing is lined to indicate contrasting colors.

I claim:

The ornamental design for a brush display, substantially as shown and described.
